(57) **CLAIM**

The ornamental design for a combined cushion and frame module for patient interface, as shown and described.

DESCRIPTION

FIG. 1 is a front perspective view of a combined cushion and frame module for patient interface showing a first embodiment of our new design in an environment of use; FIG. 2 is an enlarged perspective view of the cushion and frame module shown in isolation;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a reverse perspective view thereof;

FIG. 10 is a front perspective view of a combined cushion and frame module for patient interface showing a second embodiment of our new design in an environment of use;

FIG. 11 is an enlarged perspective view of the cushion and frame module shown in isolation;

FIG. 12 is a front view thereof;

FIG. 13 is a rear view thereof;

FIG. 14 is a top view thereof;

FIG. 15 is a bottom view thereof;

(Continued)

FIG. 16 is a left side view thereof;
 FIG. 17 is a right side view thereof; and,
 FIG. 18 is a reverse perspective view thereof.
 The broken line showing of the sample model patient and patient interface in FIGS. 1 and 10 depicts environment and forms no part of the claimed design. All other broken lines depict portions of the combined cushion and frame module for patient interface that form no part of the claimed design. Line shading and stippling in FIGS. 1-9 have been used to indicate a contrast in appearance.
